PATENTED OCT. 30, 1906.

R. W. McILVAINE.
TROLLEY TRACK SWITCH.
APPLICATION FILED DEC. 21, 1905.

UNITED STATES PATENT OFFICE.

ROBERT WARREN McILVAINE, OF WESTERN SPRINGS, ILLINOIS.

TROLLEY-TRACK SWITCH.

No. 834,483.

Specification of Letters Patent.

Patented Oct. 30, 1906.

Application filed December 21, 1905. Serial No. 292,708.

To all whom it may concern:

Be it known that I, ROBERT WARREN McILVAINE, a citizen of the United States, residing at Western Springs, in the county of Cook and State of Illinois, have invented new and useful Improvements in Trolley-Track Switches, of which the following is a specification, reference being had to the accompanying drawings, forming a part thereof.

10 The purpose of this invention is to provide an improved switch for trolley-tracks having the specific purpose of diminishing the angle of deflection necessary at any one point in order to accomplish a given total deflection between the divergent tracks connected with the switch.

It consists of the features of construction set out in the claims.

In the drawings, Figure 1 is a plan view 20 of a trolley-track junction comprising my improved switch. Fig. 2 is a section at the line 2, 2 on Fig. 1. Fig. 3 is a detail inner side elevation of the switch and connected tracks. Fig. 4 is a plan view showing a modification in which the switch member has more than two sections.

A represents a piece of track from which lead two divergent branches, one of which, the track B, may be considered as the continuation 30 of the track A and with it constituting what may be termed the "main" line A B, and the other B' may be considered the "branch." The distinction between the main line and the branch is, however, a mere convenience 35 for designation, except that the two tracks which are referred to as together constituting the main line are connected rigidly with the switch-supporting bracket; but it is immaterial whether the two pieces of track thus connected are in a straight line or are divergent.

C is a bracket which rigidly connects the two pieces of track A and B on the side opposite that past which the trolley-arm hangs, so that it does not interfere with the passage of the trolley, and it will be understood that the trolley necessarily passes on the side toward the branch track B'. The switch element of the track comprises two sections D and D', of which D is pivotally connected at one end 45 with the track-piece A and the section D' is pivotally connected to the other end of the section D and has the end remote from its pivot adapted to reach to the proximate ends of either the track B or the track B' 50 when the entire switch is adjusted for said

connections, respectively. The switch-section D' is rigid with and may be formed integrally with an operating-arm D², which extends horizontally off from the section D' at the side on which the bracket C is located, and this bracket is formed with a web C', on which the arm D² of the switch-section D' may ride in the horizontal swinging movement of the switch, as hereinafter described. Preferably said arm D² is itself 6c webbed, as shown, constituting substantially a triangular plate extension of the switch-section D', which is cast integrally with said plate-like or webbed arm. Said arm is, as shown, substantially right-angled triangular 70 in form, and at the oblique angle remote from the switch-section D' it has a boss d², in which there is mounted a vertical pivot-bolt E and which extends down through a slot C² in the web C' of the bracket C, and below said 75 bracket said pivot-bolt is provided with a flanged head or nut E', whose flange runs on the under side of the bracket-web. The slot C² extends at an angle of about forty-five degrees to the main line A B and guides the pivot-bolt seat (the boss d²) in that course in any movement which may be given to the parts. On the bracket C, outward or back from the outer end of the slot, there is pivoted a weighted or tumble-bob lever F, having the 8c weight F' at one end and an eye F² at the opposite end for connection with the pull-handle G. For supporting and affording fulcrum to this lever the bracket C has two lugs C³ C³ extended in direction parallel to the slot C², 90 with an interval or opening (seen at C⁴) between them, through which opening the lever extends, the gudgeons F³ F³ on the lever affording it pivotal bearing in said fulcrum-supports C³, which latter are upwardly open, 95 so that the gudgeons may be introduced from above and retained by cotter-pins H, inserted through the lugs above them. The tumble-bob lever is thus adapted to swing through an angle of about one hundred and 100 thirty-five degrees from the position shown in full lines in Fig. 2, at which the weighted end of the lever extends outwardly, so that the weight tends to hold said end of the lever down and the opposite end at the most elevated position which can be reached in view of the connections to the position shown in dotted lines, at which the weight is stopped at the opposite or inward side of its fulcrum, 105 such stoppage being conveniently effected by 110

the collision of the weight with the upper end of the pivot-bolt E. This pivot-bolt is connected by a link K with the lever F a short distance from the gudgeons F³ on the side 5 toward the weight F', and the rocking of the lever through the angle indicated from the first-mentioned to the latter-mentioned position therefore operates to slide the pivot-bolt seat from the outer to the inner end of the 10 slot. This movement of the pivot-bolt seat at the corner of the triangular arm D² swings the switch element, comprising both its sections D and D', in a definite path, in which the position of both sections is positively controlled throughout the entire movement, for 15 it will be evident that the pivot d of the two sections D D' to each other can move only in an arc about the pivot d' of the section D to the track A, and since the path of the 20 pivot-bolt E is positively controlled by the slot C² said pivot d must at all times be at an invariable distance from a definite point in the path of the axis of the pivot-bolt E, and these two conditions fix absolutely the position of the pivot d at all stages of the movement of the pivot E in the slot, and the section D' and the arm D² being a unitary rigid structure two points of which are determined the entire unitary structure D' D² must move 25 in a determined path. The length of the slot C² and the throw of the link K caused by the rocking of the tumble-bob lever are such as to move the farther end of the switch-section D' from a position in line with the track B 30 to a position in line with the track B'. 35

Since at each limit of the rocking movement of the lever the eye at the end of the arm opposite the weight is at a position above the lowest which it can reach in the 40 rocking movement, it will be seen that a downward pull upon this end of the lever from either position will lift the lever to a point directly above its fulcrum, and such pull being given quickly the momentum of 45 the weight will carry it over the fulcrum and complete the movement to the opposite limit from that occupied when the pull was given. A downward pull, therefore, upon the pull-handle G will shift the switch from either 50 track connection to the other, and the position in which the pull-handle stands will indicate to the operator whether the switch is in one position or the other.

For assistance in understanding the action 55 I have shown in a conventional manner a trolley L in full line on the track A. This requires no further or more specific explanation.

In Fig. 4 there is shown a modification in 60 which the switch member has three sections, and this may indicate the possibility of any desired number. In order that the several joints at which the several sections when there are more than two are connected to 65 each other may permit the folding or flexure

of the switch to a proper limit only at each joint, so that the total angular deflection may be distributed among the several joints, it is necessary that the flexure of each joint should be limited, so that no joint can be 70 folded beyond its proper proportion, and for this purpose in this invention each of the junctions—to wit, of the section D to the main line A, of the section D' to the main line B', and of the section D^a to the sections 75 D and D', respectively—is formed by pivot d^a intermediate two shoulders d^b d^b at opposite sides of the pivot on each of the sections, said shoulders being at an angle to each other less than one hundred and eighty degrees by 80 the amount of angular movement which must occur at the joint in properly moving the switch from connection with one track to the other. The element D' is operated in this construction precisely as in that shown in 85 Fig. 1.

I claim—

1. A trolley-track switch comprising, in combination with a main-line track, a bracket rigid with respect to said main-line track and extending off laterally therefrom; a movable member whose length is made up of two sections pivoted together, one section being pivoted to the main-line track, and means on the bracket for guiding in a definite path a 90 point on the other section remote from the pivot of the two sections to each other.

2. A trolley-track switch comprising, in combination with the main-line track, a switch element consisting of two sections 100 pivoted to each other, the first section being pivoted to the main line of the track, a bracket rigid with respect to the said main-line track and extending off laterally therefrom, the second switch-section having an arm 105 extending off at the same side; a guide on said arm and a guide-track for the same on the bracket, and means for moving the guide along the guide-track.

3. A trolley-track switch comprising, in 110 combination with the main-line track and a branch track, the main-line track having a gap and a bracket spanning the gap and extended off laterally at one side of the track, a switch member adapted to extend across the 115 gap, consisting of two sections pivoted to each other, the first section having the end remote from said pivot pivotally joined to the main-line track, the second section having an arm extending off laterally at the 120 same side as the bracket, said bracket having a guide-track oblique to said second switch-section, said arm of said section having a guide engaging the track, and means for moving the guide along the guide-track.

4. A trolley-track switch comprising, in combination with the main-line track having a gap therein and a branch track, a switch member adapted to extend from one end of the gap to the branch track or the other end 125 130

of the gap in the main line; a bracket rigid with the main-line track at the side thereof opposite that at which the branch track is located; a tumble-bob lever mounted on said bracket for swinging in a vertical plane, said switch member comprising two sections pivoted to each other, the first section being pivoted to the main-line track at the end of the gap opposite the branch track; a link connecting the other section with the tumble-bob lever, and means for guiding the pivot of the link to said member in a definite path.

5. A trolley-track switch comprising, in combination with a main-line track, a switch element consisting of a plurality of sections pivoted together; a bracket rigid with respect to the main-line track extending off laterally therefrom, the first section of the switch element being pivoted to the main-line track; means on the bracket for guiding in a definite path a fixed point of the last section, and means for limiting the flexure of the joints connecting the sections.

6. A trolley-switch comprising, in combination with a main-line track and a branch track, the main-line track having a gap, a bracket rigidly connecting the two parts of the main-line track separated by the gap, such bracket being extended off laterally at the opposite side of the main-line track from the branch track; a switch member adapted to extend in the gap consisting of a plurality of sections pivoted together, the first section being pivoted to the main-line track, and means on the bracket for guiding in a definite path oblique to the last section a point on said last section remote from its pivot.

In testimony whereof I have hereunto set my hand, in the presence of two witnesses, at Chicago, Illinois, this 16th day of December, 1905.

ROBERT WARREN McILVAINE.
